[57] CLAIM

The ornamental design for the ciphertel unit enclosure, as shown and described.

DESCRIPTION

FIG. 1 is a top, left and front side view showing our new design for a ciphertel unit enclosure;

FIG. 2 is a rear elevational view thereof;

FIG. 3 is a right side view thereof; and,

FIG. 4 is a bottom elevational view thereof.

The broken line showings in FIGS. 1 and 2 are for illustrative purposes only and form no part of the claimed design.
